ILLUMINATING PROJECTILE

Leonard P. Frieder, Long Island, and Walter S. Finken, Brooklyn, N. Y., assignors, by mesne assignments, to Reconstruction Finance Corporation, Philadelphia, Pa., a corporation of the United States

Application May 20, 1947, Serial No. 749,228

21 Claims. (Cl. 102—60)

1

Our invention relates to illuminating projectiles and more particularly a projectile adapted to be fired from a rifled gun barrel at high velocity, which projectile is fitted with a fuse adapted to ignite a charge to expel a flare together with a parachute for supporting it whereby to illuminate a preselected terrain at any desired point in the trajectory of the projectile.

In the illuminating projectiles of the prior art, it has been necessary to provide them with a fuse which will function to ignite a charge to expel a separable canister, housing a flare and a parachute for supporting it, at a point in the trajectory of the projectile where the velocity of motion has been reduced considerably. Furthermore, the trajectory has been such that the angle of departure has been fairly high. When it has been attempted to fire illuminating projectiles of the prior art with flat trajectories or when it has been attempted to accelerate the expulsion of the flare from the mother projectile, the attempts have been attended with failure. The principal cause of these failures have been due to two main reasons. The mother projectile gyrates around its longitudinal axis due to the impetus of the rifling in the gun barrel. When the expulsion charge in the mother projectile expels the separable canister containing the parachute and the flare, both the parachute pack and the flare are rotating at the same velocity, at the instant of expulsion. The parachute, however, tends to open immediately and since it is lighter in weight and greater in area than the flare chamber, its rotation is very rapidly retarded while the flare canister continues to gyrate under its greater momentum and velocity. This differential rotation is normally neutralized to some extent by a ball bearing swivel between the flare canister and the parachute. When the parachute opens, however, the parachute tends to become the center around which the canister gyrates. The uncompensated differential axial rotation and the radial gyration cause the shroud lines linking the parachute to the flare chamber to become twisted, thus fouling the parachute and preventing it from opening properly and remaining open to function as a retarding member.

In those cases where the fouling of the shroud lines has been insufficient to prevent the parachute from opening, the shock of opening early in the trajectory while the mother projectile is traveling at a comparatively high velocity has caused the parachute to fail either in the parachute canopy per se or in the point of attachment between the parachute and the canister.

2

One object of our invention is to provide an illuminating projectile which may be set to expel the flare and the parachute at any desired point in its trajectory and operate with certainty and precision by overcoming the failures exhibited by the illuminating projectiles of the prior art.

Another object of our invention is to provide an illuminating projectile which may be fired along a much flatter trajectory than has been heretofore possible with illuminating projectiles.

A further object of our invention is to provide an illuminating projectile in which the twisting of the shroud lines is prevented.

Other and further objects of our invention will appear from the following description.

In general our invention contemplates the use of a parachute having a hemispherical canopy and a floating hem cord such as described in United States patent to Walter S. Finken, 2,412,392, dated December 10, 1946, for supporting an illuminating candle flare or the like. The parachute and the flare are assembled in a separable canister and retained in assembled position by releaseable means. We provide means for releasing the retaining means after a predetermined interval sufficient to permit the gyration or rotation of the separable canister assembly after expulsion from the mother shell to diminish to such point that the danger of twisting or fouling the shroud lines by differential rotation between the supporting parachute and the supported flare is obviated. In order to reduce the time interval we may if desired provide retarding fins adapted to damp the rotation of the canister so that it will reach a slower speed more quickly. Then, too, the fins reduce the orbital effect of the canister traveling around the parachute with the shroud lines as a radius. A pilot parachute is provided to stream the main parachute quickly when the separable canister is permitted to part and further to reduce loss of altitude of the canister during the interval of delay between its expulsion in assembled form and its release for separation.

In the accompanying drawings which form part of the instant specification and which are to be read in conjunction therewith and in which like reference numerals are used to indicate like parts in the various views:

50 Figure 1 is a sectional view of an illuminating projectile showing one embodiment of our invention.

Figure 2 is an elevation of the canister assembly removed from the mother projectile.

55 Figure 3 is a sectional view taken on the line 3—3 of Figure 2.

Figure 4 is a view of a detail showing the fusible link which holds the canister assembly in assembled position.

Figure 5 is a perspective view showing one of the separable canister elements.

Figure 6 is a perspective view with a part broken away of one of the springs adapted to hold the split sleeves in assembled position.

Figure 7 is a perspective view with a part broken away of the other of the springs adapted to hold the split sleeves in assembled position.

More particularly, referring now to the drawings, the illuminating projectile comprises a body 8 of any desired cross sectional shape forming the main portion of a shell adapted to be fired from a rifled gun barrel. Rotating bands 10 and 12 of copper or the like are provided, as is well known to the art. The rotating bands coating with the rifling of the gun barrel rotate the entire projectile as it passes through the gun barrel. The base of the projectile is closed by a base plate 14 normally secured to the body 8 by means of metal shear pins 16. A time fuse 18 of any suitable construction is adapted to be screwed into the ogive 20 of the projectile. The forward portion of the projectile is loaded with an expulsion charge 22 of any suitable propellant or explosive. A cylindrical sleeve 24 is lodged within the body of propellant 22 to support a metal plate 26. The metal plate 26 is provided with blow holes 28. A heavy paper ring 30 rests upon the metal plate 26. A felt washer 32 covered with an upper paper layer 34 and a lower layer 36 is supported by the ring 30. The felt washer 32 is provided with a plurality of ports 38 communicating with the blow holes 28. Resting upon the heavy paper ring 30, we provide a pair of semi-cylindrical sleeves 40 and 41, one of which is shown in perspective in Figure 5. The sleeves are held in assembled relation by any appropriate means. We prefer to use a pair of elongated spring members 42 and 43 which are retained in assembled position by means of a fusible link indicated generally by the reference numeral 44. The canister formed by the semi-cylindrical sleeves, held in assembled position by the springs 42 and 43 and the fusible link 44, form a housing in the upper part of which we lodge a parachute 46 provided with shroud lines 48 secured at their lower ends to a metal swivel member 50. The lower portion of the housing formed by the separable sleeves 40 and 41 houses a container 52 in which is positioned the illuminating charge 54 of any appropriate type. The upper wall 56 of the container is formed with a boss 58 to which is secured a socket member 60 which, together with the swivel member 50, forms a parachute connection between the parachute and the flare container 52. The upper portions of the sleeves 40 and 41 are formed with a groove 62, in which a paper cover disk 64 is adapted to seat. The base plate 14 of the projectile is provided with a rabbet 66 adapted to hold a pilot parachute or disk 68 to the upper periphery 70 of the sleeves 40 and 41. If desired, the upper surface 70 of the split sleeves may be formed with a rabbet 72 to receive the edge of the pilot parachute or disk 68. The pilot parachute or disk has its shroud lines 74 connected to the upper portion of the main parachute 46.

The springs 42 and 43 are provided with oblique edges 74 and 76 providing tapered areas for the fins 80. Secured to each of the semi-cylindrical sleeves 40 and 41 in any suitable manner as by rivets or spot welds 78, we provide spring fins 80,

as can readily be seen by reference to Figures 2 and 3. These fins normally lie closely adjacent to the outside of the walls of the split sleeves 40 and 41, and are formed of light metal having sufficient inherent elasticity to move outwardly to the position shown in Figure 3 when the canister assembly is expelled from the mother shell.

The lower portion of container 52 is provided with a time delay charge 82 separated from the illuminating charge 54 by means of a combustible partition, provided with a fuse port 86. The fusible link indicated generally by reference numeral 44 is positioned within the time delay charge 82, as can readily be seen by reference to Figure 1. The powder charge 82 may be cast with the fuse rods assembled therein. If desired, the charge 82 may be formed with a recess through which the rods may be passed. The fusible link comprises an internally threaded ferrule 88 adapted to seat in the elongated spring member 42 and a similar internally threaded ferrule 90 adapted to seat in the elongated spring member 43. A wire 92 has one end thereof threadedly positioned in the ferrule 88. A wire 94 has its end threadedly positioned in the ferrule 90. The wires 92 and 94 are formed with hook portions 96 and 98 normally secured to each other by means of a low melting body of solder 100. The releasable means for retaining the split sleeves may be made of a continuous strip of fusible metal or of a textile cord such as nylon, silk, cotton, ramie or the like which will melt or burn to release the sleeves.

Referring now to Figure 5, the split sleeve 40 is formed with an upper flange 102 on the upper surface 70 of which the pilot parachute normally rests. The recess 104 formed by the downwardly extending portion of the flange 102 is adapted to receive the upper edges 106 and 108 of the elongated spring members 42 and 43. Each of the sleeves 40 and 41 are provided with an internal shoulder 110, upon which the upper portion of the flare container 52 is adapted to rest. Recesses 112 and 114 are provided in the edges of the split sleeves to permit the passage of the ferrules 88 and 90. The lower flanges 116 of the split sleeves rest directly upon the paper ring 30 which is supported by the metal plate 26. The lower surface of the base plate 14 rests upon the upper flange 70 of the split sleeves 40 and 41. It will be seen that besides forming a housing for the flare and parachute, the split sleeves act as thrust transmitting members through which the force of the expulsion charge 22 acts to shear pins 16 and drive off the base plate 14.

It is to be understood that any suitable means for holding the split sleeves in assembled position may be employed as, for example, wires, straps or the like. The securing means is normally held in secured position by means of a fusible connection adapted to be released after the passage of a predetermined period of time. It is to be understood further that while we have shown a powder train to introduce the time delay, any equivalent means for introducing time delay to release the split sleeves may be employed.

For purposes of illustration, we show the means for securing the split sleeves to comprise a pair of elongated spring members shown in Figures 6 and 7. The lower edge 118 of spring member 42 and the lower edge 120 of spring member 43 are normally semi-circular in shape, and lie along a radius which is shorter than the radius of the external surface of the split sleeve members 40 and 41. The upper edges 106 and 108 of the elongated spring members 42 and 43, when in

untensioned position, lie along the locus of an ellipse whose major axis is slightly less than the external diameter of the assembled split sleeves 40 and 41. The elongated spring members 42 and 43 are formed of light spring metal. They are provided with upper and lower tapered corrugations 122 and 124. The depth of the corrugations increases from lateral edges 74 and 76 toward a position intermediate the edges; that is, the corrugations are greatest at the center line and tapered to zero at the edges. These grooves lend stiffness to the elongated spring members 42 and 43.

In the assembly of the elongated spring members around the split canister formed by the members 40 and 41, the upper edges 106 and 108 are seated in the groove 104 formed by the flange 102. To accomplish this, the upper peripheries 106 and 108 of the elongated spring members 42 and 43 must be forced around a cylinder of larger diameter. The spring members tend to contract camming them from the curved surface presented by the assembled split sleeves 40 and 41. Since the lower peripheries 118 and 120 of the elongated spring members are of smaller diameter than the upper peripheries 106 and 108, the lower peripheries must be stretched through a greater amplitude to be forced around the cylindrical surface presented by the assembled split sleeves 40 and 41. The split sleeves therefore in assembled position are under a graduated tension, the tension being greater at the lower end. The tendency for the spring members is to cam out from the cylindrical surface of the assembled split canister under the inherent tension of the spring members. This tendency is resisted adjacent the upper peripheries of the elongated spring members by the groove 104. The lower ends of the elongated spring members are normally prevented from moving out by the fusible link 44. Accordingly, the assembled canister will appear as shown in Figure 2.

In operation the projectile is assembled as shown in Figure 1. The fuse is set for the desired point of the trajectory at which the expulsion of the flare or illuminating candle is to occur. When the projectile is fired the fuse 18 is armed and its time delay initiated as is well known to the art. The fuse 18 is adapted after a predetermined delay to ignite the expulsion charge 22. The ignition of this charge forces the plate 26 rearwardly toward the base. The split canister transmits the thrust of this expulsion to the base plate 14 shearing the relatively soft metal pins 16, expelling the assembly comprising the split canister held in position by the elongated springs from the interior of the mother projectile 8. The base plate 14 being heavier drops away freeing the pilot parachute 68. A lanyard 71 attached to the apex of the pilot chute extends within the master parachute compartment to a point of attachment on the master parachute load line adjacent the swivel 50. This permits the pilot chute to carry the load prior to the opening of the split canister and the release of the master canopy. The fins 80 extend from their housed position, acting to damp the multiple gyrations of the assembly. The pilot parachute tends to reduce the velocity of travel of the assembly. The ignition of the expulsion charge 22 blows through the blow holes 28 and through the ports 38 to ignite the time delay powder charge 82 which burns progressively over a predetermined period of time. The rate of burning is dependent, of course, on the chemical composition of the

constituents of the powder, its physical condition and the pressure under which it is packed, as is well known to the art. As the powder burns, the entire assembly is held in its assembled position, shown in Figure 2. When the powder reaches the position of the fusible link, the heat of burning will melt the solder 100. We may employ, for example, a solder melting in the vicinity of 370° F. The outward force developed by the elongated spring members 42 and 43 tends to move the arms 96 and 98 of the wires 92 and 94 toward each other. This is resisted by the solder 100 which is positioned therebetween. As soon as the solder melts the lower portions of the spring members 42 and 43 spring outwardly, tilting the free edges of the upper surfaces 106 and 108 of the elongated spring members 42 and 43. The action is progressive from bottom to top of the split sleeves occupying a very short interval of time. The elongated spring members therefore are hurled outwardly free of the split canister. The time which elapsed between the expulsion of the canister from the mother shell and the releasing of the elongated spring members is sufficiently long so that the canister no longer rotates or gyrates at such high velocity as to cause fouling of the shrouds of the main supporting parachute when it opens. As soon as the spring members are thrown clear, the residual centrifugal force of such rotation as remains throws the canister members 40 and 41 outwardly freeing the parachute and flare container 52. When a long period of time delay is employed, the centrifugal force is reduced and the split sleeves free the master parachute falling away by gravity. The disk 64 is likewise freed of the grooves 62 formed in the internal wall of the split sleeve members 40 and 41. The pilot parachute now streams the main parachute and twisting of the shrouds is prevented by the swivel joint between the shroud lines and the container 52. In the meantime, the powder train 82 has ignited the flare material 54 through the fuse port 86 and the flare candle performs its function of illuminating the surrounding terrain. It is to be understood, of course, that the entire assembly is still traveling forward at considerable velocity. Our parachute construction, however, is such as to take this shock due to the principles of construction of the parachute as taught in the Finken Patent 2,412,392, referred to above.

While we have shown the use of a pair of fins for slowing the rotation of the canister assembly after expulsion, a larger number of fins may be employed. In such case the fins may be attached to the elongated spring members if desired.

It will be seen that we have accomplished the objects of our invention. We have provided an illuminating projectile which may be set to expel a canister comprising a flare and a parachute at any desired point in its trajectory without incurring the danger of failure by fouling of the parachute shrouds or by failure of the parachute itself. We have provided an illuminating projectile which may be fired along a much flatter trajectory than has heretofore been possible with illuminating projectiles. Our time delay feature prevents the fouling of the shroud lines. The split canister opens with precision after a predetermined period of time at which the gyration of the canister and parachute assembly has been reduced to a point at which the swivel connection between the parachute and the illuminating candle is sufficient to prevent fouling of the shroud lines.

It will be understood that certain features and sub-combinations are of utility and may be employed without reference to other features and sub-combinations. This is contemplated by and is within the scope of the claims. It is further obvious that various changes may be made in details within the scope of the claims without departing from the spirit of the invention. It is, therefore, to be understood that this invention is not to be limited to the specific details shown and described.

Having thus described our invention, we claim:

1. A projectile including in combination a projectile body formed with a chamber, a cover plate for closing said chamber, releasable holding means for securing said cover plate in chamber-closing position, a canister positioned in said chamber, said canister comprising a sleeve formed by a plurality of separable members, a parachute housed within said canister, a body within said canister adapted to be supported by the parachute, means for connecting said body to said parachute, means for holding said separable members in assembled position, an expelling charge for ejecting said canister from said chamber, a fuse for igniting said expelling charge at a predetermined point in the travel of said projectile and time delay means for rendering said releasable holding means inoperative after a predetermined interval of time following expulsion of the canister from said chamber.
2. A projectile as in claim 1 in which said means for releasably securing said cover plate comprises a plurality of shear pins.
3. A projectile as in claim 1 in which said separable members are formed with portions of different thickness whereby to form a sleeve of different internal diameters.
4. A projectile as in claim 1 including in combination a pair of fins and means for securing one of said fins to each of said separable members.
5. A projectile as in claim 1 in which said body adapted to be supported by said parachute comprises an illuminating candle.
6. A projectile as in claim 1 in which said means for connecting said parachute to said body includes a swivel permitting relative rotation between said parachute and said body.
7. A projectile as in claim 1 in which said means for holding said separable members in assembled position comprises a pair of elongated curved spring members.
8. A projectile as in claim 1 in which said means for holding said separable members in assembled position includes a pair of elongated curved spring members, said spring members having their lower edges formed along the locus of a circle having a smaller radius than the external diameter of said sleeve and their upper edges formed along the locus of an ellipse having its major axis shorter than the external diameter of said sleeve.
9. A projectile as in claim 1 in which said means for holding said separable members in assembled position includes a pair of elongated spring members formed with a curved cross section, means carried by said separable members for holding the upper edges of said springs adjacent the exterior surfaces of said separable members, a pair of links respectively secured to one of the respective spring members adjacent their lower ends and releasable means for securing said links to each other.
10. A projectile as in claim 1 in which said means for holding said separable members in

assembled position includes a pair of elongated spring members formed with a curved cross section, means carried by said separable members for holding the upper edges of said springs adjacent the exterior surfaces of said separable members, a pair of links respectively secured to one of the respective spring members adjacent their lower ends, fusible means for releasably securing said links to each other and said time delay means comprises a powder train adapted to be ignited by said expelling charge for fusing said fusible means after a predetermined interval of time.

11. A projectile as in claim 1 in which said time delay means for rendering said sleeve-holding means inoperative comprises a pair of links, fusible means for holding said links in connected relation and a powder train adapted to be ignited from said expelling charge for fusing said fusible means after a predetermined interval of time.

12. A projectile as in claim 1 in which said separable members are formed with an internal groove and a cover disk having its edges positioned within said groove.

13. A projectile as in claim 1 including in combination a disk positioned between said canister and said expelling charge, said separable members extending between said disk and said cover plate whereby to transmit the thrust of said expelling charge to release said releasable plate-holding means.

14. A projectile as in claim 1 including in combination a disk positioned between said canister and said expelling charge, said time delay means including a powder train and a port in said disk to permit said expelling charge to ignite said powder train.

15. A projectile as in claim 1 in which said body adapted to be supported by said parachute comprises a casing, pyrotechnic illuminating composition positioned in said casing, said time delay means for rendering said sleeve-holding means inoperative including a powder train and means for igniting said pyrotechnic illuminating composition from said powder train.

16. A projectile as in claim 1 in which said cover plate is formed with a rabbet, said cover plate contacting said separable canister members in the region of said rabbet whereby to form a recess therewith, a pilot disk having its edges positioned in said recess and means for connecting said pilot disk to said parachute.

17. A projectile as in claim 1 in which the upper surface of said separable canister members are formed with a rabbet adapted to form a recess with said cover plate, a pilot disk having its edges positioned in said recess and means for connecting said pilot disk to said parachute.

18. In a device of the character described, a canister comprising a sleeve formed by a plurality of separable members, a parachute housed within said canister, a body within said canister adapted to be supported by said parachute, means for connecting said body to said parachute, means for holding said sleeves in assembled position and time delay means for rendering said sleeve-holding means inoperative after a predetermined interval of time whereby to permit said separable members to separate to free said parachute for the support of said body.

19. A device as in claim 18 in which said time delay means includes a powder train, a member adapted to be rendered ineffective under the influence of the heat of combustion of said

powder train, said member being normally under tension and positioned in proximity to said powder train.

20. A device as in claim 18 in which said time delay means includes a powder train, a fusible member adapted to be melted under the influence of the heat of combustion of said powder train, said member being normally under tension and positioned in proximity to said powder train.

21. A device as in claim 18 in which said time delay means includes a powder train, a combustible member adapted to be burned under the influence of the heat of combustion of said powder train, said member being normally under tension and positioned in proximity to said powder train.
